MULTIPLE-FUSE PLUG.

Application filed May 6, 1922. Serial No. 559,075.

To all whom it may concern:

Be it known that we, WILLIAM H. TAYLOR, a subject of the King of Great Britain, and CHARLES W. DOWNS and JACOB W. BARBEY, citizens of the United States, residing at Detroit, county of Wayne, State of Michigan, have invented a certain new and useful Improvement in Multiple-Fuse Plugs, and declare the following to be a full, clear, and exact description of the same, such as will enable others skilled in the art to which it pertains to make and use the same, reference being had to the accompanying drawings, which form a part of this specification.

This invention relates to multiple fuse plugs and the object of the invention is to provide a fuse plug having a series of fuse elements therein, means being provided for connecting one of the elements at a time in the circuit, the said means including indicating means to indicate which fuse element is connected. With the fuse plugs now commonly in use containing a single fuse element when the fuse element is blown it is necessary to discard the entire fuse plug as being unfit for further use and therefore one of the main objects of the invention is to provide a fuse plug of the character described which may be blown a number of times before being discarded. Another object of the invention is to provide a fuse plug of the character described provided with means for separately indicating which fuse elements are blown and which are not blown. A novel feature of the invention resides in the provision of means for indicating which fuse element is in the circuit in combination with means for indicating whether or not the said fuse element is blown, said indicating means also indicating the fuse elements which are not blown so that the user may easily change the contact from a blown fuse element to one which is not blown. A further object of the invention is to provide a multiple fuse plug which is very simple and efficient in operation and in which the change from one fuse to another within the plug may be very easily accomplished. These objects and the several novel features of the invention are herein-after more fully described and claimed, and the preferred form of construction by which these objects are attained is shown in the accompanying drawings in which—

Fig. 1 is an elevation of a multiple fuse plug embodying our invention. 55
 Fig. 2 is a plan view of the fuse plug. 60
 Fig. 3 is a vertical section through the fuse plug. 65
 Fig. 4 is a bottom view of the fuse plug. 70
 Fig. 5 is an elevation of the fuse plug with the casing removed. 75
 Fig. 6 is a perspective view of one of the fuse elements. 80
 Fig. 7 is a plan view of the cover for the body of the fuse plug before being folded. 85
 The fuse plug comprises a main body 1 of porcelain or other insulating material and a series of notches or apertures 2 are formed in this body 1 which open at 3 through the upper enlarged part 4 of the body as shown in Fig. 3. The enlarged portion 4 of the porcelain is provided with a series of gas vents 5 shown more particularly in Fig. 5, the upper face of the porcelain being flat to receive a mica disc 6 which is cemented thereon. The lower end of the plug is provided with a series of notches 7 as shown in Figs. 4 and 5 corresponding to the number of notches 2 and in alignment therewith. 90 These notches 7 are each provided with a flat seat 8 adapted to receive the ends 9 of the fuse elements 10. The fuse elements 10 are each provided with a narrow portion 11 which will blow when too great a load is placed on the circuit. The fuse elements are positioned with the ends 9 thereof engaging the seat 8 of the notches 7 and extend upwardly through the notches 2 so that the highest portion thereof is the portion 11 95 which is the nearest to the mica cover 6. After the fuse elements have been set in place a paper ring 12 is slipped thereover having a series of radiating portions 13 which are bent upwardly to cover the notches 2 as shown in Figs. 5 and 7. This ring 12 may be of paper as stated or may be made from a sheet of asbestos paper the object being to prevent the burning through of the threaded brass shell or casing 14 when the fuse elements are blown. A fibre or asbestos ring 15 is positioned over the paper ring 12 and is cemented in place, the said ring 15 engaging the fuse elements 10 and holding the ends 9 thereof in place in the notches 7. The brass shell 14 is then slipped in place and is secured to the porcelain by indenting the casing 14 at two diametrically

- opposite points 16 which forces a part of the casing into the two diametrically opposite notches 17 of the porcelain shown in Figs. 1, 2 and 5. This supports the threaded 5 casing solidly on the porcelain so that it cannot be moved in relation thereto and the ends 18 of the fuse elements are bent over the upper edge of the shell 14 as shown in Fig. 3 and a drop of solder is applied to the end 10 18 of each fuse element as shown in Fig. 1 to secure the same to the casing and form a good contact. A cap 19 is then positioned over the upper end of the casing and covers the edge of the mica disc 6, the lower edge 15 20 of the cap being inturned beneath a shoulder 21 formed in the porcelain to hold it in place. The body 1 is provided with a central aperture 22 opening into a recess 23 in the upper end of the body and a brass rod 20 24 extends upwardly through the aperture 22 and is provided with a pointer 25 on the upper end thereof within the recess 23. A coiled spring 26 is interposed between the pointer 25 and the lower end 27 of the recess 25 23 about the rod 24 and holds the pointer and rod in the uppermost position. The rod 24 at the lower end is provided with a portion 28 having an upwardly extending point 29 which extends into the notch 7 and contacts the end 9 of the fuse element therein 30 due to the tension of the spring 26.
- When the fuse plug is threaded into a socket the brass shell 14 forms the outer contact member and the portion 28 of the 35 rod 24 forms the central contact member. In the position shown in Fig. 3 the flow of current is through the member 28, point 29, through the fuse element on the right of Fig. 3 and portion 11 thereof and thence to 40 the casing 14. When the fuse element is blown the break occurs in the portion 11 thereof which, being near the mica disc 6 blackens the portion of the mica disc directly over the respective opening 3 and as 45 the disc 6 is cemented to the porcelain only the portion of the mica directly over the respective opening can be blackened, the gases escaping through the vent 5 and between the cap 19 and portion 4 of the porcelain. By 50 concentrating the blowing of the fuse to a very small portion of the mica disc the mica over the respective opening is colored a dense black so that no mistake can be made in distinguishing between a fuse that is 55 blown and one that is not. Also by cementing the mica disc to the porcelain it is impossible for any of the mica to be blackened except in the portion directly over the blown fuse element. By pulling down on the portion 60 28 the rod 24 is drawn downwardly thus compressing the spring 26 and the point 29 is inserted in another notch 7 and when released the point 29 will be forced into contact with the portion 9 of the respective fuse 65 element by the spring 26 thus connecting a

new fuse element in the circuit. It is also to be noted that the point 25 is directly over the point 29 and always points to and indicates which fuse element is in the circuit. In other words—the fuse element contacted by the point 29 so that it is very simple to remove the plug from the socket and set the contacts to connect an unblown fuse element in the circuit. 70

The fuse plug, as hereinbefore described, 75 is efficient in operation for all the ordinary purposes but we have found it advisable to introduce what we have termed an arc breaker which is shown at the right side of Fig. 3 at 50. This consists of a strip of insulating material positioned in and extending from the inner end of the fuse chamber practically to the bottom of the bend of the fuse member 11 and adapted to be readily inserted in the chamber after the fuse element is in position. It will be noted from Fig. 3 that, with the fuse blowing at the point of the bend, which is the point of least resistance, the arc would tend to pass between the broken ends and, due to introduction of the member 50, the arc necessarily travels around the end of the strip 50. This strip electrically shields the legs of the bend one from the other so that the arc tends to immediately become lengthened about the 80 end of the member 50 and blows out almost immediately and therefore produces minimum degree of heat and little internal pressure in the fuse chamber. Without the shield 50 the arc continues to lengthen until 85 a high degree of heat is developed in the fuse chamber resulting in a high internal pressure and puncture of the shield 14. We have shown only one arc breaker 50 but it is to be understood that the plug may be used with all the fuse chambers provided with the arc breakers or without depending upon the amperage of the current in the system in which the fuse plug is to be used. 90

It is further to be noted that the vents 5 100 vent to atmosphere between the flange of the cap and the body 4 of the porcelain member as the cap does not in practice fit so tightly on the member 4 as to prevent an egress of gases therebetween. 115

From the foregoing description it becomes evident that the device is very simple and efficient in operation, is of comparatively low manufacturing cost and provides a fuse plug which may be used many times before being discarded and which accomplishes the objects described. 120

Having thus fully described our invention, what we claim is—

1. In a fuse plug, a body of insulating material having a central longitudinal aperture and a series of longitudinal apertures spaced radially thereabout, the lower end of the body being provided with a series of notches arranged radially between the cen- 125

- tral aperture and the series of apertures, a transparent disc cemented on the upper face of the body and covering the apertures therein, a series of fuse elements each having an end extending into one of the notches of the body, the said fuse elements each extending upwardly into one of the series of apertures and being provided with a portion of least current capacity adjacent the central aperture and each having a portion of least current capacity adjacent the transparent disc, a metal shell secured to the lower end of the body and closing the series of apertures opening therethrough, 70 the opposite ends of the fuse elements being secured to the said shell, a rod rotatably mounted in the central aperture provided with a return bent end adapted to engage the lower ends of the fuse elements, a pointer on the upper end of the rod in alignment with the return bent end and a spring holding the return bent end of the rod in contact with the respective fuse element. 75
5. In a fuse plug, a body of insulating material having a lower end of smaller diameter than the upper end and having a series of apertures through the upper end of the body and through the sides of the lower end thereof, the said body being also 80 provided with a central aperture, a series of fuse elements each positioned in one of the series of apertures of the body and having the lower ends thereof arranged radially about the central aperture, a transparent disc secured on the upper face of the body, the fuse elements being each provided with a portion of least current capacity adjacent the transparent disc, a metal shell secured to the lower end of the body, the opposite ends of the fuse elements being secured to the said shell, a rod rotatably mounted in the central aperture provided with a contact point adapted to engage the lower ends 85 of the fuse elements, and a pointer on the upper end of the rod in alignment with the said contact point. 90
6. In a fuse plug, a body of insulating material having a central longitudinal aperture and a series of longitudinal apertures spaced radially thereabout, the lower end of the plug being provided with a series of notches in radial alignment with the series 95 of longitudinal apertures, a transparent disc cemented on the upper face of the body and covering the apertures therein, a series of fuse elements each mounted in one of the series of spaced longitudinal apertures, the said fuse elements being each provided with a portion of least current capacity extending adjacent the transparent disc, each fuse element being provided with an end extending into one of the notches of the body, a metal shell secured to the body, the opposite ends of the fuse elements being secured to the metal shell, a rod rotatably mounted in the central aperture of the body, a pointer on the upper end of the rod, the said rod being 100 provided with a return bent end adapted to engage the ends of the fuse elements in the notches of the body, and yieldable means allowing positioning of the said return bent end in any of the series of notches, the said yieldable means holding the return bent end in contact with the respective fuse element when the rod is released. 105
7. In a fuse plug, a body of insulating material having a lower end of smaller diameter than the upper end, the said body being provided with a central aperture and a series of apertures arranged thereabout opening through the sides of the lower end of the body, a series of fuse elements each 110 positioned in one of the series of apertures and having the lower ends thereof arranged radially about the central aperture of the body, a transparent disc secured to the upper face of the body and covering the apertures therein, the fuse elements extending upwardly into the apertures and each having a portion of least current capacity adjacent the transparent disc, a metal shell secured to the lower end of the body and closing the series of apertures opening therethrough, 115 the opposite ends of the fuse elements being secured to the said shell, a rod rotatably mounted in the central aperture provided with a portion adapted for contact with the ends of the fuse elements in the notches of the body, yieldable means holding the said end in contact with the respective fuse element in a notch, and means exposed to view through the transparent disc indicating the fuse element contacted by the said rod portion. 120
8. In a multiple fuse plug, a body of insulating material having a central longitudinal aperture, a series of fuse chambers 125

- formed in the surface of the said body circumferentially in spaced relation thereabout, said chambers opening through the surface of the body for a portion of their length 5 adjacent the inner end and continuing as apertures extending through the head of the plug, a fuse element for each of the chambers having a portion extending upwardly in the aperture of its chamber having a portion 10 of least current capacity adjacent the end thereof, a metal shell encircling the plug and with which the ends of the fuse elements are connected, an insulating member covering the open portion of the fuse 15 chambers held in position at the upper end by the said shell and shielding the shell to prevent injury thereof by fusing of any fuse element, said elements each having the lower ends projecting beyond its chamber at 20 the inner end of the body, a ring like member of insulating material adapted to be inserted over the fuse elements holding the said projecting ends of the elements in position and lying between the inner end of the said 25 shell and the said elements, a contact member in the central longitudinal recess having a part thereof adapted to be positioned to engage the projecting ends of any one of the said fuse elements, and a transparent 30 element sealed to the head of the body closing the fuse chamber apertures therein.
7. In a multiple fuse plug, a body of insulating material having a central longitudinal aperture, a series of fuse chambers 35 formed in the periphery of the body opening through the face thereof, an insulating member covering the openings of the fuse chambers, the central portion of the body extending beyond the inner ends of the fuse 40 chambers, a series of fuse elements one for each of the said chambers and having an end extending over the said projecting end of the body, a threaded shell about the body to the outer end of which the fuse elements 45 are connected, the said insulating material being held in place at the outer end by the shell and sealing the chamber, a ring extending over the inner ends of the fuse elements about the projecting end of the body, 50 said ring supporting the insulating material at the inner ends of the fuse chambers and separating the fuse elements and inner end of the shell, a central contact member adapted to be manually positioned to engage the bent end of any one of the said fuse elements, and a transparent element sealing the outer ends of the fuse chambers, said chambers being vented.
8. In a multiple fuse plug, a body having 55 a central longitudinal aperture, a central contact member extending therethrough, a series of fuse chambers positioned in spaced relation about the periphery of the body opening through each end thereof and through the side of the body for a portion 60 of its length adjacent the inner end, a threaded metal shell about the said body, a foldable insulating fire resistant member fitting over the inner end of the body and extending about the sides thereof enclosing 70 the open sides of the fuse chambers, a fuse element in each of the chambers, the upper end of which is electrically connected with the shell, said fuse elements having a bent portion extending toward the outer end of the fuse chamber and provided with a portion 75 of least current carrying capacity near the said end and extending thence to the inner end of the body extending outwardly of the fuse chamber, a ring member of insulating material positioned about the lower end of the body and securing the projecting ends of the fuse elements in position, said member supporting the fire resistant material at the inner ends of the fuse chambers 80 and separating the shell and fuse elements at the said inner end, said central contact member being adapted to be manually positioned to engage any one of the fuse elements, a transparent member sealed to the outer end of the body, and a cap on the outer end of the body each of the fuse chambers having a vent aperture opening beneath the cap.
9. In a multiple fuse plug, a series of fuse chambers positioned circumferentially thereabout in spaced relation and opening through the periphery of the body, an insulating member providing a cover for the open sides of the chambers, a metal shell 95 about the body supporting the outer end of the insulating material, a fuse element in each of the chambers connected at the outer end to the outer end of the shell, and a contact member positioned to engage the inner end of any one of the fuse elements.
10. In a multiple fuse plug, a body of insulating material having a series of fuse chambers extending in spaced relation about the body and open through the side thereof adjacent the inner end, the upper end of the body being enlarged and the chambers extending therethrough, an insulating member 100 of flexible material adapted to be secured to the inner end of the body and having a series of flaps of a width to cover the open side of each of the chambers sealing the inner open end and open side thereof, a metal shell about the inner end of the body extending thereover and securing the free ends of the said flaps in position, a fuse element in each chamber having the outer end connected to the outer end of the shell, extending outwardly therefrom and having a bent portion extending adjacent to the outer end of the chamber, a portion of least current carrying capacity being provided at the bend, a transparent member covering the outer end of the body closing the open ends 105 of the fuse chambers, the inner ends of the
- 110

- 120
- 125
- 130

fuse elements extending through the inner end of the respective chamber, a ring like member of insulating material engaging over said inner ends of the elements holding

5 the same in position and separating the said ends from the inner end of the shell, and a central contact member adapted to be manu-

ally positioned to engage any one of the inner ends of the fuse elements.

In testimony whereof, we sign this specific- 10
cation.
